UNITED STATES PATENT OFFICE

THEODORE G. McGIRR, OF BROOKLYN, NEW YORK, ASSIGNOR TO MAGAZINE REPEATING RAZOR COMPANY, OF NEW YORK, N. Y., A CORPORATION OF NEW JERSEY

BLADE HOLDER FOR RAZOR SHARPENING MACHINES

Application filed March 7, 1927. Serial No. 173,580.

This invention is a blade holder for razor sharpening machines and is intended, more particularly, to properly support single edged blades during the sharpening thereof.

5 The primary object of the present invention is to provide a holder especially adapted to firmly grip and support unbacked, single edged blades of the character employed in safety razors.

10 Speaking generally, the holder of this invention embodies a rigid back portion which carries two laterally extending opposed clamping jaws which are relatively resilient. A blade slot is formed between the marginal edges of these jaws and is of normally less width than the thickness of the blades so that when the blades are introduced into the slot the jaws will be sprung apart and placed under sufficient stress to tightly grip the 15 blades and hold them against inadvertent release.

The blade slot is of a depth appreciably less than the width of the individual blades and its base forms a shoulder against which 20 the rear edges of the blades seat.

25 In practice, one of the jaws is preferably rigid and the other resilient. The rigid jaw may be integral with the rigid back portion, but I prefer to make both the rigid and resilient jaws, as well as the back portion separately, and thereafter assemble them to form a 30 complete holder. In this embodiment of the invention, the rigid back portion is channelled along its forward edge to provide a seat in which the rigid and resilient jaws are introduced and thereupon riveted permanently in position.

In practice, the jaws may extend uninterrupted throughout the length of the holder, but, if desired, one or both of said jaws may be built up of a number of parts positioned side by side longitudinally of the holder.

It is of pronounced practical importance in 40 a holder embodying the present invention to so construct the holder that the blades will be gripped between clamping jaws while the rear edges of the blades seat against a suitable non-yielding shoulder which serves to hold the blades firmly against retracting 45 from the sharpening wheels. This is the es-

sence of this invention and the invention is not limited to details of jaw construction.

Features of the invention, other than those adverted to, will be apparent from the hereinafter detailed description and claims, when 55 read in conjunction with the accompanying drawing.

The accompanying drawing illustrates different practical embodiments of the invention, but the construction therein shown is to 60 be understood as illustrative, only, and not as defining the limits of the invention.

Figure 1 is a perspective view showing a 65 blade holder embodying this invention with the blades removed.

Figure 2 is an end view of the holder as shown in Figure 1.

Figure 3 is a fragmentary perspective view illustrating one end portion of the holder with a blade in place therein.

Figure 4 is an enlarged fragmentary end elevation showing the tips of the clamping jaws. In full lines, the jaws are shown in the positions which they occupy when the blades are removed and in dotted lines, I 75 have shown the manner in which the resilient jaw is sprung away from the rigid jaw when the blade is introduced between said jaws.

Figure 5 is a perspective view showing a 80 slightly modified form of the invention.

Figure 6 is a section on the lines 6—6 and 6a—6a of Figure 1.

Referring to the drawing, 1 designates a rigid back plate or plate of the holder. In practice, this back plate is preferably shaped for cooperation with the stationary guide or shoe of a blade sharpening machine, so that the said back plate 1 may be slid along said guide to bring the blades associating with the holder consecutively into cooperative relation with the rough grinding, fine grinding, honing and stropping machines.

In the preferred form of construction shown in the drawing, the back plate 1 is provided in its forward edge with a channel 2, 95 in which the rear margins of the jaws 3 and 4 are seated and firmly and rigidly held in place by rivets 5. The jaws extend for an appreciable distance beyond the forward edge of the rigid back plate and they are 100

preferably externally beveled or tapered as clearly shown at 6 and 7 to reduce the dimension of their edges to a minimum in order that they may work close to the sharpening wheels. The back plate 1 and the clamping jaws 3 and 4 are of a suitable length or extent to receive a plurality or series of blades to be sharpened.

It will be noted from Figure 2 in particular that those portions of the jaws which seat in the channel 2 are proportioned to completely fill the channel, i. e., their aggregate thickness is substantially equal to the width of the channel, so that when the jaws are secured in place by the rivets 5, the rigid back will be fixedly secured to said jaws.

As further shown in Figure 2, the rigid jaw is provided with a rib 8', which is formed on the inner face of said jaw and extends longitudinally thereof in parallel relation to the free edge of the jaw. The forward edge of this rib forms a shoulder 8, which is spaced from the free edge of the jaw a distance appreciably less than the width of the blades 25 with which the holder is adapted for cooperation. The inherent resiliency of the jaw 3 normally causes said jaw to seat upon the face of the rib 8' and said rib is made, in practice, to have a height slightly less than the thickness of the blades, so that when the blades are introduced into the blade slot 9 and into a position to rest against the shoulder 8, said jaws will be forced apart and the resilient jaw placed under sufficient stress to 35 properly grip the blades and hold them in position.

The inner faces of the jaws, rearwardly of the shoulder 8, may be of any suitable shape without departing from this invention, as 40 the fundamental concept of the invention resides in the provision of the blade slot with an associated shoulder. However, it is found, in practice, that the resilient jaw may, to advantage, be undercut as shown at 10 in 45 order to increase its resiliency. It is also entirely practical to cut away the resilient jaw at its exterior face instead of its interior face for the purpose of increasing its resiliency, but this is optional.

50 The jaws should be so formed that the thickness of the blade slot will normally be slightly less than the thickness of the blades and the cooperating surface of said jaws forwardly of the shelf should be substantially 55 parallel in order to insure efficient gripping of the blades.

The normal relative positions of the jaws are shown in full lines in Figure 4. Here it will be seen that the jaw 3 normally rests on 60 the face of the rib 8'. However, when a blade is introduced between the jaws, the jaw 3 is sprung away from the jaw 4, as shown in dotted lines in Figure 4, to receive the blade X. The resilient jaw is thus placed 65 under sufficient stress to properly maintain

the blade in position and to preclude its inadvertent release.

In practice, the blades may be introduced into the holder in any suitable manner. For example, the outer ends of the jaws may be internally beveled or rounded as shown at 70 11 in Figure 6, so that the blades may be successively slipped into cooperative relation with the jaws as indicated by the arrow in Figure 3. However, if it be desired to insert 75 the blades through the free ends of the jaws and in a direction perpendicular to the shoulder 8, the outer edges of the jaws may also be formed as shown in Figure 6.

80 In Figure 1, the resilient jaw 3 is shown in one piece which extends the full length of the holders with slots 12 extending from the free edge of said jaw toward the rigid back and for an appreciable distance. These slots are spaced apart a distance substantially equal to the length of a blade, so that slight variations in the thickness of consecutive blades may be properly compensated for and will not interfere with the proper gripping 85 of the blades individually. Instead of making the resilient jaw in one piece as shown, it may be divided into a succession of separate jaws designated 3a in Figure 5. This is an alternative construction and is optional.

90 It will be apparent from the foregoing detailed description that the holder of this invention is extremely simple in construction. It may be economically manufactured and is thoroughly efficient in its operation. The advantage of employing a shoulder against 95 which the rear edges of the blades firmly seat will be apparent to those skilled in the art. By the use of such shoulder the blades are accurately positioned and are precluded from shifting during the sharpening operations. The blades are held firmly in place 100 in the holder and may be accurately guided through the shoe or guide of the sharpening machine.

110 The accompanying drawing shows the holder constructed to support four blades. In practice, however, it may be made to support a greater or less number. The invention is therefore to be understood as not being limited to exact details of construction, as shown 115 in the drawings, but is to be understood as fully commensurate with the appended claims.

120 Having thus fully described the invention, what I claim as new and desire to secure by Letters Patent is:

1. A blade holder for sharpening machines comprising an elongated rigid back plate, and clamping jaws rigidly fixed to said back plate and of sufficient length or extent to hold a plurality of blades, one of said jaws having an inner rib of less height than the thickness of the blades to be sharpened, so that the normal space between the outer gripping edges of said jaws will be less than the thick- 125 130

ness of the blades to be inserted in the holder, thus enabling the jaws to properly grip and hold the blades; one of said clamping jaws being rigid and the other resilient, said rigid 5 jaw extending uninterruptedly the whole length of the holder, the said resilient jaw being divided to afford a plurality of clamping fingers adapted to engage the blades individually, thus adapting the holder to grip 10 blades of slightly varying thicknesses properly.

2. A blade holder for sharpening machines comprising an elongated rigid back plate, and clamping jaws rigidly fixed to 15 said back plate and of sufficient length or extent to hold a plurality of blades, one of said jaws having an inner rib of less height than the thickness of the blades to be sharpened, so that the normal space between the 20 outer gripping edges of said jaws will be less than the thickness of the blades to be inserted in the holder, thus enabling the jaws to properly grip and hold the blades, said back plate being provided with a groove or 25 channel in which the backs of the clamping jaws fit.

In testimony whereof I have signed the foregoing specification.

THEODORE G. McGIRR.
